ATTORNEYS

UNITED STATES PATENT OFFICE.

JOHN M. TATUM, OF ATHENS, TEXAS.

DESIGN FOR A TOBACCO-PIPE.

No. 40,209.

Specification for Design.

Patented Aug. 10, 1909.

Application filed June 9, 1909. Serial No. 501,215. Term of patent 14 years.

To all whom it may concern:

Be it known that I, JOHN M. TATUM, a citizen of the United States, residing at Athens, in the county of Henderson and State of Texas, have invented a new, original, and ornamental Design for a Tobacco-Pipe, of which the following is a specification, reference being had to the accompanying drawing, forming part thereof.

The figure is a perspective view of a tobacco pipe showing my design.

I claim:

The ornamental design for a tobacco pipe, as shown.

JOHN M. TATUM.
